CLAIM

The ornamental design for an automotive test terminal, as shown and described.

DESCRIPTION

FIG. 1 is a perspective view of an automotive test terminal showing our new design;

FIG. 2 is a front elevational view;

FIG. 3 is a rear elevational view;

FIG. 4 is a left side elevational view;

FIG. 5 is a right side elevational view;

FIG. 6 is a top plan view; and,

FIG. 7 is a bottom plan thereof.

FIGS. 1-3, 6 and 7 have been drawn on an enlarged scale with respect to FIGS. 4 and 5.

FIG. 1

FIG. 2

FIG. 3

FIG. 4

FIG. 5

FIG. 6

FIG. 7
